Specification for Design.

Patented May 20, 1913.

Application filed June 3, 1912. Serial No. 701,457. Term of patent 7 years.

To all whom it may concern:

Be it known that I, FREDERICK B. MALLORY, a citizen of the United States, residing at Portland, in the county of Multnomah and State of Oregon, have invented a new, original, and ornamental Design for Block Sides, of which the following is a specification, reference being had to the accompanying drawing, forming part thereof, in which—

Figure 1 is a front view of my invention;

Fig. 2 is a side elevation of same, and Fig. 3 is the reverse side of Fig. 1.

I claim:

The ornamental design for a block-side as shown.

In testimony whereof I hereunto affix my signature in the presence of two witnesses.

F. B. MALLORY.
